HEAT EXCHANGER

Robert H. Shaw, East Hartford, Conn., assignor to United Aircraft Corporation, East Hartford, Conn., a corporation of Delaware

Application October 26, 1954, Serial No. 464,751

9 Claims. (Cl. 257—154)

This invention relates to a condenser or a surface type heat exchanger.

An object of this invention is to provide a condenser or heat exchanger which is formed having small diameter tubes arranged to present rows of polygonic openings therethrough.

Another object of this invention is to provide a condenser or heat exchanger in which metal shells or ducts fit in the polygonic openings formed by the small diameter tubes and provide the main cross-flow passages through said tubes.

A further object of this invention is to provide a condenser or heat exchanger having smooth passageways through the small tubes provided with fin and stiffening means therein.

Another object of this invention is to provide a condenser or heat exchanger having means along the inner surface of the smooth passageways to disturb the boundary layer therethrough and to direct some fluid directly around the small tubes.

Further objects and advantages will be apparent from the following specification and drawing:

Figure 1 is a front elevational view of a condenser or heat exchanger embodying the invention.

Figure 2 is a figure taken along the line 2—2 of Figure 1 on an enlarged scale.

Figure 3 is a perspective view of an end portion of a shell or duct provided to form a smooth passage through the small diameter tubes.

Referring to the figures, the invention is shown embodied in a condenser or heat exchanger 1. This heat exchanger is a cross-flow type of one-pass arrangement and comprises a main flow duct or chamber 3 and a fluid header system 5. The gas or fluid flow duct or chamber 3 is formed rectangular in shape having sides 9 and 11, a top 13 and a bottom 15. Top 13 forms the bottom of inlet header chamber 41 of the fluid header system 5 which also includes sides 42, 44 and a top 46. An inlet header 48 directs the fluid into the inlet header chamber 41. Sides 9 and 11 are fixed to the top 13 of the chamber 3. Bottom 15 forms the top of outlet header chamber 50 of fluid header system 5 which also includes sides 52, 54 and a bottom 56. An outlet header 58 directs the fluid out of outlet header chamber 50. Sides 9 and 11 extend over the edges of bottom 15 and slidably engage the sides 52 and 54, respectively, of the outlet header chamber. This provides for expansion and contraction of the fluid flow tubes 20. Sides 9 and 11 are formed as solid plates while the top 13 and bottom 15 are each formed as a plate having a like series of lines of holes therein extending from one end of the chamber 3 to the other.

As viewed in Figure 1 there are nine lines of these holes, lettered *a* through *i*. Each line of holes contains the same number of holes and starts at the same distance from the front of the plate in which it is located, that is, either top 13 or bottom 15. Each hole has the diam-

2

eter of the inner diameter of the fluid flow tube connected thereto. The distance between the centers of these holes in each line in the top 13 and bottom 15 is arranged so that the outer diameters of adjacent fluid flow tubes adjacent this point barely touch. This relationship can be seen in the three lines of tubes at the right of Figure 2. While the fluid flow tubes have been described as abutting the upper plate, they may be arranged so as to extend through said upper plate.

10 Extending through the gas flow duct or chamber 3 between top 13 and bottom 15 are a plurality of fluid flow tubes 20. These tubes are arranged in nine banks, 20a, 20b, 20c, 20d, 20e, 20f, 20g, 20h and 20i. Each fluid flow tube abuts the bottom of top 13 in a position over its respective hole and is affixed to the top. At its other end each tube abuts the top of the bottom 15 in a position over its respective hole, the hole having the same location in the bottom 15 that the hole to which the other end of the fluid flow is attached has in the top 13, and is affixed to the bottom 15. While the fluid flow tubes have been described as abutting the lower plate, they may be arranged so as to extend through said lower plate.

Each fluid flow tube 20 is formed having a serpentine shape. Each end of each fluid flow tube 20 is formed as a short straight tubular section 22. These two sections are coaxially positioned. This is shown by axis A—A in Figure 1. As the fluid flow tube 20 extends from the lower tubular section 22 toward the other, a short straight tubular section 24 forms an angle of approximately 60° with the axis A—A of the sections 22. Next, a short straight tubular section 26 extends from the end of section 24 located away from axis A—A, in a direction parallel to the axis A—A formed by the sections 22 and for a distance approximately equal to the length of section 24. A short straight tubular section 28 then extends from the end of section 26 not attached to section 24, to the axis A—A forming an angle of 60° therewith. The next tubular section, section 30, 35 extends coaxially with sections 22 from the end of section 28 which is on the axis A—A, for a distance approximately equal to the length of section 24. It is noted that tubular sections 24, 26, 28 and 30 are all of approximately the same length. This forms the tubular sections 24, 26 and 28 into a half polygonic shape or extension. The end of section 30 not attached to section 28, then extends into another tubular section 24. Each tubular section 24 along a fluid flow tube lies in a common plane. The sequence of tubing sections 24, 26, 28 and 30 then continues until the desired height is reached, then in the last sequence, section 28 is connected to the top tubular section 22. In Figure 1, the first row of tubes is shown as having five half polygonic extensions 40 extending to the left of axis A—A before the top 13 of the heat exchanger is reached.

To form the construction shown in Figure 1 these fluid flow tubes 20 are arranged from the front of the gas flow duct or chamber 3 to the rear in the following manner. As mentioned above, a fluid flow tube 20 extends between the first hole of each line of holes of the top 13 and its respective hole in bottom 15 with the half polygonic extensions extending to the left and all lying in a plane perpendicular to the direction of gas flow through said heat exchanger. This forms the first row of tubes. The next row of tubes has a fluid flow tube 20 extending between the second hole of each line of holes of the top 13 and its respective hole in bottom 15 with the half polygonic extensions extending to the right and all lying in a plane perpendicular to the direction of gas flow through said heat exchanger. This arrangement of the tubes is carried on in this sequence

to the rear of the heat exchanger, that is one row of tubes having its polygonic extension extending to the left with the next row of tubes having its polygonic extension extending to the right. While this is clearly shown in Figure 1, Figure 2 gives evidence of the sequence as it progresses to the rear of the heat exchanger. With the half polygonic extensions all lying in planes which are perpendicular to the same reference, adjacent tubes 20 have their sections 26 and 30 in contact. The one exception being some of the sections 26 of the fluid flow tubes on each end, that is in banks *a* and *i*.

With the fluid flow tubes arranged in their banks as disclosed above, it can be seen that polygonic openings 32 are formed through said heat exchanger in the direction of gas flow through said heat exchanger. Some of these openings are formed by the placing of the half polygonic extensions of one bank with the other half polygonic extensions of the same bank, and the other polygonic openings are formed between the banks of fluid flow tubes.

Each opening 32 has fixed therein a metal shell or duct 34. These shells can be fixedly mounted by any means desired. These shells or ducts 34 are each provided with two fins 36 of corrugated cross section extending between the edges of two opposing sides. These corrugated fins provide means for transferring heat and strengthening the structure. The corrugations provide a greater surface area for heat transfer and permit the expansion and contraction of the metal shells or ducts without setting up undue stresses. Fins 36 are held in spaced relation by louvers 38 and 40. Louvers 38 and 40 are spaced along the length of the metal shell or duct 34 to disturb the boundary layer of the gas flow to the duct and to direct some gas directly around the fluid flow tube. The louvers 38 (see Figure 2) provide turbulence to disturb the boundary layer while louvers 40 both direct fluid against the fluid flow tubes and disturb the boundary layer through the duct 34. The fins 36 and louvers 38 and 40 are merely shown in seven of the metal shells or ducts 34 so that the arrangement of the fluid flow tubes may be more clearly viewed. Metal shells or ducts of irregular shapes are provided around the outer edge of the heat exchanger to conform with the shape of the openings such as at 70, 72 and 73.

It is to be understood that the invention is not limited to the specific embodiment herein illustrated and described, but may be used in other ways without departure from its spirit as defined by the following claims.

I claim:

1. In combination, a flow chamber, a plurality of fluid flow tubes passing through said chamber, said tubes being arranged in a plurality of banks, each bank of tubes having a plurality of tubes extending in a line lengthwise of said chamber, adjacent tubes in the line of said fluid flow tubes being formed with complementary oppositely offset portions to present a plurality of openings extending lengthwise of said chamber each having parallel side walls, at least some of said openings having a metal shell fitted therein, said metal shell having fins located therein extending lengthwise of said chamber, each fin extending from one parallel side wall of the shell to another, said fins being corrugated with the corrugations running lengthwise of the shell.

2. In combination, a flow chamber, a plurality of fluid flow tubes passing through said chamber, said tubes being arranged in a plurality of banks, each bank of tubes having a plurality of tubes extending in a line lengthwise of said chamber, adjacent tubes in the line of said fluid flow tubes being formed with complementary oppositely offset portions to present a plurality of openings extending lengthwise of said chamber each having parallel side walls, at least certain of said openings having a metal shell fitted therein, said metal shell having two fins located therein extending lengthwise of said chamber, each fin extending from one parallel side wall of the shell to another.

another, said fins dividing said metal shell into three passages, each passage having a louver on a shell portion of its surface.

3. In combination, a flow chamber, a plurality of fluid flow tubes passing through said chamber, said tubes being arranged in a plurality of banks, each bank of tubes having a plurality of tubes extending in a line lengthwise of said chamber, adjacent tubes in the line of said fluid flow tubes being formed with complementary oppositely offset portions to present a plurality of polygonic openings extending lengthwise of said chamber each having pairs of parallel side walls, each polygonic opening having a metal shell fitted therein, each metal shell having pairs of parallel side walls conforming to the walls of said opening and having two fins located therein extending lengthwise of said shell, each fin extending transversely of its shell from one of the parallel side walls to the other parallel side wall, said fins being corrugated with the corrugations running lengthwise of the shell, a plurality of louvers in said parallel side walls extending down the length of each metal shell and projecting into said shell between said fins, said louvers and the angularly related side walls adjacent said parallel side walls cooperating to position said fins against displacement in said shells.

4. In combination, a flow chamber, a plurality of fluid flow tubes passing through said chamber, said tubes being arranged in a plurality of banks, each bank of tubes having a plurality of tubes extending in a line lengthwise of said chamber forming a plurality of rows, each fluid flow tube being formed in a serpentine manner having a plurality of half polygonic shapes extending to one side of its axis, each half polygonic shape having a tubular section at its outer extremity which is parallel to the axis of the fluid flow tube, each fluid flow tube in the first row of tubes having its half polygonic shapes extending towards one side of said chamber, each fluid flow tube in the second row of tubes having its half polygonic shapes extending to the other side of said chamber, the tubular section of a fluid flow tube in the first row of a bank being positioned abutting and in front of the tubular section of a fluid flow tube in the second row of an adjacent bank, polygonic openings being formed through said tubes between two adjacent banks of tubes and between rows in a bank of tubes.

5. In combination, a flow chamber, a plurality of fluid flow tubes passing through said chamber, said tubes being arranged in a plurality of banks, each bank of tubes having a plurality of tubes extending in a line lengthwise of said chamber forming a plurality of rows, each fluid flow tube being formed in a serpentine manner having a plurality of half polygonic shapes extending to one side of its axis, each half polygonic shape having a tubular section at its outer extremity which is parallel to the axis of the fluid flow tube, each fluid flow tube in the first row of tubes having its half polygonic shapes extending towards one side of said chamber, each fluid flow tube in the second row of tubes having its half polygonic shapes extending to the other side of said chamber, the tubular section of a fluid flow tube in the first row of a bank being positioned abutting and in front of the tubular section of a fluid flow tube in the second row of an adjacent bank, polygonic openings being formed through said tubes between two adjacent banks of tubes and between rows in a bank of tubes, at least some of said openings having a metal shell positioned therein, said metal shell having fins located therein, each fin extending from one side of the shell to another, said fins being corrugated with the corrugations running lengthwise of the shell.

6. In combination, a flow chamber, a plurality of fluid flow tubes passing through said chamber, said tubes being arranged in a plurality of banks, each bank of tubes having a plurality of tubes arranged in a line lengthwise of said chamber, adjacent tubes in each bank be-

ing formed with a plurality of complemental oppositely offset portions spaced along the length of the tubes forming a plurality of passages extending lengthwise of said chamber, said offset portions having parallel side walls, the adjacent parallel side walls of said flow tubes in adjacent banks overlapping each other, at least some of said passages having a tubular metal shell fitted therein extending lengthwise of said chamber and having parallel side walls corresponding to the side walls of said offset tube portions, said shells having fins located therein, each fin extending from one side wall of the shell to the other parallel side wall, said fins being corrugated with the corrugations running lengthwise of said shell.

7. In combination, a flow chamber, a plurality of fluid flow tubes passing through said chamber, said tubes being arranged in a plurality of banks, each bank of tubes having a plurality of tubes arranged in a line lengthwise of said chamber, adjacent tubes in each bank being formed with a plurality of complemental oppositely offset portions spaced along the length of the tubes forming a plurality of passages extending lengthwise of said chamber, said offset portions having parallel side walls, the adjacent parallel side walls of said flow tubes in adjacent banks overlapping each other, at least some of said passages having a tubular metal shell fitted therein extending lengthwise of said chamber and having parallel side walls corresponding to the side walls of said offset tube portions, each of said shells having two fins located therein, each fin extending from one side wall of the shell to the other parallel side wall, and means for locating said fins including louvers in said parallel side walls at spaced points along the length of said shells having tabs displaced inwardly from said side walls and projecting between said fins in planes transverse to the planes of said fins.

8. In a heat exchanger, a gas flow chamber having top and bottom walls provided with vertically aligned holes therein arranged in a plurality of lines extending lengthwise of said chamber, a first row of tubes extending between the first hole of each line of holes of said top and corresponding holes in said bottom, said first row of tubes having polygonic extensions spaced along the length of the tubes and extending to the left and all lying in a plane perpendicular to the direction of gas flow through said heat exchanger, a second row of tubes extending between the second hole of each line of holes of said top and the corresponding hole in said bottom, said second row of tubes having polygonic extensions located oppo-

site the extensions in said first row of tubes but extending to the right and all lying in a plane perpendicular to the direction of gas flow through said heat exchanger, the tubes in the corresponding holes of each line of holes forming banks of tubes running lengthwise of said chamber, the left and right polygonic extensions of which are complemental and define a plurality of polygonic gas flow passages extending from front to rear of said gas chamber, said extensions having parallel side walls and the parallel side walls of the extensions in one bank overlapping the adjacent side walls of the next bank.

9. In a heat exchanger, a gas flow chamber having top and bottom walls provided with vertically aligned holes therein arranged in a plurality of lines extending lengthwise of said chamber, a first row of tubes extending between the first hole of each line of holes of said top and corresponding holes in said bottom, said first row of tubes having polygonic extensions spaced along the length of the tubes and extending to the left and all lying in a plane perpendicular to the direction of gas flow through said heat exchanger, a second row of tubes extending between the second hole of each line of holes of said top and the corresponding hole in said bottom, said second row of tubes having polygonic extensions located opposite the extensions in said first row of tubes but extending to the right and all lying in a plane perpendicular to the direction of gas flow through said heat exchanger, the tubes in the corresponding holes of each line of holes forming banks of tubes running lengthwise of said chamber, the left and right polygonic extensions of which are complemental and define a plurality of polygonic gas flow passages extending from front to rear of said gas chamber, said extensions having parallel side walls and the parallel side walls of the extensions in one bank overlapping the adjacent side walls of the next bank, some of said passages having a tubular metal shell fitted therein extending lengthwise of said chamber and having corresponding parallel side walls, said shell having fins located therein, each fin extending from one parallel side wall of the shell to the other, said fins being corrugated with the corrugations running lengthwise of the shell.
